UNITED STATES PATENT OFFICE.

CHARLES H. MILLER, OF CLEVELAND, OHIO.

COMBINED COAL AND GAS RANGE.

No. 899,885.

Specification of Letters Patent. Patented Sept. 29, 1908.

Application filed December 9, 1907. Serial No. 405,674.

To all whom it may concern:

Be it known that I, CHARLES H. MILLER, a citizen of the United States, residing at Cleveland, in the county of Cuyahoga and State of Ohio, have invented certain new and useful Improvements in a Combined Coal and Gas Range, and do declare that the following is a full, clear, and exact description of the invention which will enable others skilled in the art to which it appertains to make and use the same.

My invention relates to a combined coal and gas range, and the object of the invention is to provide a range adapted to use either solid fuel or gas or vapor for heating the oven, all substantially as shown and described and particularly pointed out in the claims.

In the accompanying drawings, Figure 1 is a perspective front elevation of the range with the front plate broken away, and Fig. 2 is a cross section thereof from side to side, Fig. 1 showing the burner in closed position, and Fig. 2 showing the same open and in using position. Fig. 3 is a front to rear central sectional elevation with the parts in position as seen in Fig. 2. Fig. 4 is a perspective detail of a portion of the vapor burner and a rear damper operatively connected therewith. Fig. 5 is an enlarged cross section of the gas burner and parts of the range immediately associated therewith and with the burner in open or using position. Fig. 6 is a cross section of the range and on the axis 35 of the burner partly broken out immediately on line corresponding to 6—6, Fig. 5.

As thus shown, A represents the body of the range, F the usual firepot, a the ashpit, and O the oven located as usual in kitchen ranges with a draft flue D about the same, top, bottom and sides. A fresh air draft or passage E is provided across the bottom of the range beneath the bottom wall or floor of said hot air draft space D through which fresh air is drawn to supply combustion for both the firepot and the gas burner.

If hard fuel, like coal or wood be used, the burner B is closed by rotating the same a quarter turn into closed position, as in Fig. 1, but if said burner be in use draft through the fire-box is cut off by a rear top damper 2, through which a short draft is provided into the smoke flue G and by a down damper 3, adapted to close the draft space D downward

at the side of the oven, thus cutting off all draft through the fire pot when gas is burned. However, if hard fuel be used, the said dampers 2 and 3, or either of them, may be open or closed according as a direct or indirect draft be wanted, and said dampers have separate control. The said gas burner B has trunnions 4 at its ends on which it is adapted to make a quarter rotation, and is located in the angle of the inner wall 8 of the ashpit, the bottom o of the oven above the same and the division wall or plate 5 which separates the draft flue D from the fresh air flue or space E beneath said plate. The location of the burner in this particular angle enables a quarter rotation thereof to close all the passages about the same, as in Fig. 1, or to open the passages as in Fig. 2. To these ends the burner is provided with a flange 7 lengthwise at an inclination and of such elevation that when the burner is in closing position and out of use the said flange 7 will rest against the inner wall 8 of the ashpit, closing the upward draft between the burner and the ashpit, or between walls 8 and 14, as seen in Fig. 1. The said flange 7 is provided with an apron 9 at an inclination thereto adapted to form a stop for the burner on plate 5 and close air draft on that side, and a longitudinal rib 10 on this apron is adapted to engage in the angle of the plate 12 on bottom oven plate o and also close the draft space D against possible outlet between the two vertical walls 8 and 14, when the burner is out of use. The said burner also has another flange, 15, along its bottom and side adapted to engage the edge 90 of the intermediate wall or plate 5, Fig. 1, and cut off draft through this space or channel when the burner is closed.

The effect of the foregoing construction is to provide a free passageway at one side of burner B for fresh air to supply combustion when the burner is in use, and the flange 7 which stands on the opposite side of the burner for this passageway has sufficient elevation to cut off some of the draft from the burner upon that side and to induce the products of combustion and heat to pass more or less into the channel or space between the plates 8 and 14 into the oven as shown in Fig. 2.

A damper H is shown at the bottom of exhaust or outlet flue G beneath the oven at the rear of the range, and this damper is auto-

matically opened and closed by the burner B when rotated, so that when the burner is in use, the said damper will be closed, and when the burner is out of use the damper will be 5 open for draft from the firepot. To these ends said damper is pivoted at its bottom and adapted to swing on its pivots by engagement of the projection 20 on the end of the burner with either of the two projections 21 10 and 22 on the damper. That is to say, when the damper is closed, as in Figs. 3 to 6 inclusive, the projection or lug 20 bears upon projection 22 of the damper and rotates it into closing position, but when the burner 15 receives a quarter rotation out of use, the projection 20 strikes lug 21 on the damper and throws it back and open in the direction of the arrow, Fig. 6.

The angle plate 12 on the bottom of the 20 oven serves also to protect the oven plate from burning out by the direct heat of the burner, and a stop piece 24 is laid lengthwise with the burner along the edge of plate 5 to provide a close bearing for flange 15 when 25 the burner is closed.

Whatever products of combustion enter the oven between walls 8 and 14 pass out from the oven through holes 26 at the bottom of rear false wall 16 and thence outward by 30 flue openings 27 at the top of the rear main wall 17.

Damper plate 3 is right angled in cross section and therefore adapted to close the oven 35 openings 18 when solid fuel is being used in firepot F and to open draft flue D when the damper is in this position. When drawn outward passage or flue D is closed at its top and oven openings 18 are uncovered thus making passage D available for the upward 40 movement of heated air from fluid burner B and thereby exposing the oven at this side and bottom to the heat from said burner. The arrangement of flues and dampers, and location of the burner and fire pot in respect 45 thereto, are such that a uniform distribution of heat about the oven is always obtainable from either the fluid burner or the fire pot.

What I claim is:—

1. A kitchen range having an oven and an 50 angular heat passage about the same, and a combined fluid burner and damper located in an angle of said passage.

2. A kitchen range having an oven provided with a heat passage beneath the same 55 and a rotatable and combined fluid burner and damper in said passage.

3. A kitchen range having a fire pot and a baking oven and a heat passage beneath the oven, in combination with a rotatable burner 60 in said passage, and constructed to open and close the same.

4. A kitchen range having a baking oven and a heat passage beneath the same provided with an air intake to supply combus-

tion, and a rotatable fluid burner in said 6 passage and constructed to close said intake.

5. A kitchen range having a baking oven with a heat passage beneath and at the side thereof, an air inlet from beneath in the angle of said heat passage, in combination 70 with a rotatable burner in said angle constructed to open and close both said draft passage and said air inlet.

6. A kitchen range having a baking oven 75 and a heat passage for the products of combustion about the same, a burner in said passage adapted to be rotated, a fresh air inlet to said burner and a flange on the burner adapted to close both said air inlet and said draft space when the burner is turned out 80 of use.

7. A kitchen range having an oven and an exhaust flue and a draft passage beneath the oven provided with an opening into said exhaust flue, in combination with a rotatable 85 burner in said passage and a damper for said opening operatively connected with said burner.

8. A kitchen range having an oven and a draft passage beneath the same having an 90 outlet, in combination with a rotatable burner in said passage and a damper for said outlet, and said burner and damper provided respectively with projections at their adjacent ends constructed and arranged to open 95 and close said damper when said burner is rotated accordingly.

9. A combined gas and coal range having an oven and an angular draft flue about the same, a fire pot for solid fuel at the front of 100 said oven, and a fluid burner in said draft flue at the bottom of the oven in the angle below the fire pot.

10. A kitchen range having an oven and a heat passage on four sides thereof, a fire pot 105 open to said passage and a rotatable fluid burner at the bottom of the said oven in said passage, and a damper adapted to close communication from said fire pot through said heat passage when the fluid burner is in use. 110

11. A kitchen range having an oven and a heat passage about the same, a fire pot at the front of the range and a fluid burner located in said heat passage, and a right-angled damper plate adapted to control the 115 air draft about the oven for both said fire pot and said fluid burner.

12. A kitchen range having a fire pot and an oven and a heat passage about the four sides of said oven, and heat intake openings 120 at the top of the opposite sides of the said oven, a rotatable fluid burner at the bottom of said oven adapted to open and close said passage, and a damper for said heat passage adapted to permit the use of either the fire- 125 pot or fluid burner independently.

13. A kitchen range having an oven and an angular heat passage about the same, a

separate firepot and a rotatable fluid burner in said heat passage, and an angular damper arranged to control the flow of heat products in said passage for either said firepot or said

burner.

14. A kitchen range having an oven provided with a heat passage at each side and beneath the same, a firepot and a rotatable fluid burner open to said passage, a damper at the entrance of said passage adapted to

control the flow of the heat products from both the fire pot and the fluid burner, and a discharge flue and damper therefor for said heat passage.

In testimony whereof I sign this specification in the presence of two witnesses.

CHARLES H. MILLER.
